UNITED STATES PATENT OFFICE.

FLOYD D. HUNT, OF BURLINGTON, VERMONT.

STORM WINDOW.

1,419,384.

Specification of Letters Patent. Patented June 13, 1922.

Application filed March 2, 1921. Serial No. 449,049.

To all whom it may concern:

Be it known that I, FLOYD D. HUNT, a citizen of the United States, residing at Burlington, in the county of Chittenden and State of Vermont, have invented certain new and useful Improvements in Storm Windows, of which the following is a specification.

This invention has for its object the provision of means whereby an outside storm window or sash may be readily placed in position and secured against accidental detachment. The invention seeks to provide inexpensive means whereby to avoid the necessity of using ladders to reach an upper story and to permit the placing of the outside or storm sash through the ordinary window. The invention is illustrated in the accompanying drawings and will be hereinafter fully set forth.

In the drawings—

Figure 1 is an elevation of my improved storm sash in position against the outside of a window frame;

Fig. 2 is an enlarged detailed vertical section on the line 2—2 of Fig. 1;

Fig. 3 is a perspective view showing the parts of the fastening devices separated but in their approximate relative positions;

Fig. 4 is a perspective view of a detachable handle which may be provided to facilitate the handling of the window while it is being secured in place.

The storm window or sash comprises a frame preferably consisting of stiles 1, upper and lower rails 2 and mullion strips 3 bisecting the frame both vertically and horizontally. At about the center of the frame, I provide on the vertical mullion strip a knob or projection 4 for a purpose which will presently appear. The frame should be of such dimensions that it will fit against the outside edges of the window frame and rest upon the outside sill. In applying the invention, I employ a plurality of anchor plates 5 which consist each of an angle iron having suitable openings through one web through which screws or other fasteners 6 may be inserted into the adjacent side member of the window frame, the other web of the plate projecting laterally from the window frame and substantially flush with the outside edge thereof. I also provide upon the stiles 1 of the storm sash, a plurality of

holders 7 which are adapted to engage over the laterally projecting webs of the respec-

tive anchor plates and each of these holders consists of a metallic plate having a lateral lip 8 at one side and perforated to permit the insertion of a fastening screw or its equivalent 9 into the stile. I also provide a detachable handle 10 which is illustrated as consisting of a tube provided intermediate its ends with a keyhole slot 11, the circular portion of which will permit it to be engaged over the head of the projection 4 and bring the straight portion thereof into engagement with the shank of said projection behind the head of the same.

In placing the storm sash in position, I first secure the anchor plates 5 to the side members 12 of the window frame adjacent the outer edge thereof and then insert the sash partly through the open window and while resting the same upon the window sill, engage the handle 10 with the projection 4. By holding said handle in the left hand and grasping the inner end of the frame with the right hand, the storm sash may be easily pushed through the open window and stood on end on the outer window sill while being held close against the outer edge of the window frame by the left hand. While thus held, the holders 7 are secured in position upon the right hand stile and the fastenings 9 turned home so that the said holders will snugly engage the laterally projecting webs of the respectively adjacent anchor plates, it being understood that before the sash is brought to the window the stile will be provided with openings to receive the said fastenings located by proper measurements. After the fastenings on the lower portion of the right hand stile have been secured in place, the handle 10 is grasped by the right hand and the lower fastenings then secured in position upon the left hand stile of the storm sash. The sash of the usual window may then be lowered so that the upper anchoring members or fasteners may be placed in positions, after which the removable handle may be detached so that it will not be apt to swing around and crack the glass, it being understood that the spaces of the storm sash are glazed, as indicated at 13.

It will be readily noted from the foregoing description, taken in connection with the accompanying drawings, that I have provided an exceedingly simple and inexpensive means whereby a storm sash will be securely held in position and may be easily brought into place and as easily removed

when the warm seasons approach. The sash will not detract from the sightly appearance of the building, but will add greatly to the comfort of its occupants and while it will prevent the entrance of the elements it will permit thorough ventilation inasmuch as no matter how closely the sash may be brought against the window frame there will be sufficient leakage to permit the entrance of fresh air when the sashes of the ordinary window are raised or lowered. It will also be noted that the holding devices do not project beyond the stiles of the storm sash and there is, therefore, no diminution of the light admitted to the room. It is also obvious that the mullion strips may be arranged in such number and relative locations as to correspond

with the mullion strips of the regular window. The holder 7 may be dispensed with and the screw 9 inserted through an opening provided therefor in the lateral web of the anchor plate but I prefer to employ the holder as the sash is thereby more firmly secured in place. 20

Having thus described the invention, what is claimed as new is: 25

The combination of a storm sash having a headed projection on its inner side, and a tubular handle member provided circumferentially with a keyhole slot whereby it may be fitted over said projection and engage the shank of the same. 30

In testimony whereof I affix my signature.
FLOYD D. HUNT. [L. s.]
